UNITED STATES PATENT OFFICE.

WILLIAM H. KELLY, OF CHEYENNE, WYOMING.

GAME APPARATUS.

No. 823,049.

Specification of Letters Patent.

Patented June 12, 1906.

Application filed May 8, 1905. Serial No. 259,410.

To all whom it may concern:

Be it known that I, WILLIAM H. KELLY, a citizen of the United States, residing at Cheyenne, in the county of Laramie and State of Wyoming, have invented certain new and useful Improvements in Game Apparatus, of which the following is a specification.

This invention relates to a toy game alley; and it consists, essentially, of an elevated board having a series of numbered boxes thereon and an alley having an upwardly-curved end to guide the ball thereto, so that the element of chance may enter into the game to as great an extent as possible.

It has for its object to produce a device of this character which will be very interesting and entertaining and which is at the same time so simple in construction as to be cheaply manufactured and placed upon the market.

Reference is to be had to the accompanying drawings, in which—

Figure 1 is a perspective view of the device. Fig. 2 is a longitudinal vertical sectional view. Fig. 3 is a perspective view of a slightly-modified form.

Corresponding and like parts are referred to in the following description and indicated in all the views of the drawings by the same reference characters.

The numeral 1 designates the alley, which is provided with sides 2, which form a support for the elevated board 3. This board 3 has its upper surface partitioned and subdivided into a plurality of boxes or squares 4, which may be numbered as desired. The alley 1 may be curved upward to meet the front side of the board 3, as seen in Fig. 3, or it may pass under the board 3, as seen in Fig. 1, and terminate in an approximately semi-circular curve 5, so arranged as to throw a ball projected along the alley, so that it will fall into one of the boxes 4 on the board 3. It will be observed that the upper portion of the curve 5 is extended for a short distance along a tangent, so as to eliminate any chance of the projectile being misthrown. Where the alley curves up to the front of the board 3, it is desirable to place a stop or plate 6 at the rear thereof, so that a ball will not be thrown entirely off the board, even though it be projected along the alley with a fairly good velocity. A spring-gun 7 of any suitable construction is used in connection with the above-described apparatus to throw the projectiles.

In operation a ball is placed in the spring-gun 7 and shot or projected along the alley 1. When the ball reaches the upwardly-inclined portion, it is thrown a short distance through the air, so as to fall into one of the boxes 4, and counts for the player according to the number of the box. It will be evident that owing to the uncertainty of the action of the upwardly-curved end of the alley it will be practically impossible for the player to project the ball that it will fall into any particular box and that the result will depend almost entirely upon chance. Another point to which I wish to call attention is the fact that this game alley as constructed by me may be made of a very few pieces of sheet metal, since the sides and bottom may be made integral, and the upturned end of the alley may be made either as an extension of the board 3 or of the bottom of the device, according to the form used. While chance is a factor in playing the game, nevertheless skill acquired by practice is a controlling feature to be taken into consideration.

Having thus described the invention, what I claim as new is—

1. A game apparatus of the surface-projectile type comprising an alley provided with two longitudinal sides, a board held between said sides at one end of the alley in an elevated position, longitudinal and transverse intersecting vertical partitions on said board and dividing the same into a plurality of boxes, and said alley being provided adjacent said boxes with an upwardly-deflected portion, as and for the purpose set forth.

2. A game apparatus of the surface-projectile type comprising an alley provided with two longitudinal sides, an elevated board held between said sides at one end of the alley, longitudinal and transverse intersecting partitions on the upper surface of said board and dividing the same into a plurality of boxes, and said alley being provided at the rear end of said board with an upwardly and rearwardly curved portion, and projectiles designed to travel over said alley and be returned by the curved end thereof into the said boxes, as and for the purpose set forth.

In testimony whereof I affix my signature in presence of two witnesses.

WILLIAM H. KELLY. [L. S.]
